S. LADINSKY

WINDOW SASH HOLDER

Filed June 19, 1922

INVENTOR
STANLEY LADINSKY.

BY *Marin Levy*
ATTORNEY

UNITED STATES PATENT OFFICE.

STANLEY LADINSKY, OF NEWARK, NEW JERSEY.

WINDOW-SASH HOLDER.

Application filed June 19, 1922. Serial No. 569,365.

To all whom it may concern:

Be it known that I, STANLEY LADINSKY, a citizen of Poland, residing at Newark, in the county of Essex and State of New Jersey, have invented certain new and useful Improvements in Window-Sash Holders, of which the following is a specification.

This invention relates to improvements in devices for maintaining window sashes in adjusted position in their frame and has as its object to provide an efficient means for accomplishing such purpose.

A further object is in the provision of means wholly contained within themselves for holding the window sash at any point within its frame without manual operation.

These objects are attained by the novel construction, arrangement and combination of parts, hereinafter described and shown in the accompanying drawing, forming a material part of this disclosure, and in which:—

Figure 1 is a fragmentary partial, side elevational, partial sectional view of a conventional type of window and frame, illustrating the application of the invention.

Figure 2 is a side elevational view of the friction device in detail.

Figure 3 is a transverse sectional view taken on line 3—3 of Figure 2.

In the drawings, the numeral 10 designates generally the wooden window frame, rabbeted as at 11 to provide guides for the sash 12 carrying the pane 13.

At the bottom of the rabbet or groove 11 is a relatively deep slot 14 in which is secured a rack 15, as shown in Figure 1.

The corners of the sash are cut away as at 16 and mounted on the surface thus produced are a pair of opposed brackets 17 held by screws 18 in firm engagement with the sash.

Formed with each bracket are raised flanged elements 20 in which is secured a spindle 21 held from rotation by keys 22.

Loosely mounted on the spindle are a pair of discs 23 having between them a central disc 24 held to the spindle by a key 25.

A casing comprised of a circular plate 26 formed with a cylinder 27 and covered by

another plate 28, is freely mounted on the spindle 21, said casing filling the space between the bracket elements 20.

A pair of opposed spiral springs 29 are interposed between the inner surfaces of the casing side elements and the discs 23 pressing the latter into frictional engagement with the center disc 24 and the ends of said springs are turned outwardly to engage in openings formed in their respective abutting members.

Formed on the periphery of the cylinder 27 are gear teeth 30 meshing with the rack 15 combined torsional effect of the springs and their pressure as applied to the discs, the window sash is held at any height desired.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention and set forth the manner of its construction, application and use, what I claim as new and desire to secure by Letters Patent, is:—

1. In a window sash holder, the combination with a recessed frame and a sash slideable therein, of a rack fixed in said frame at the bottom of the recess, one or more brackets carried by said sash, a spindle fixed in said bracket, a hollow gear rotatable on said spindle meshing with said rack, and frictional retarding means carried internally of said gear.

2. In a window sash holder, the combination with a recessed frame and a sash slideable therein, of a rack fixed in said frame at the bottom of the recess, one or more brackets carried by said sash, a spindle fixed in said bracket, a hollow gear rotatable on said spindle meshing with said rack, a disc keyed centrally of said spindle, discs rotatable on said spindle engaging the sides of said fixed discs, and opposed springs fixed at one end in the side of said gear and at their other end in said loose discs.

3. In a window sash holder, the combina-

tion with a recessed frame and a sash slide-
able therein, of a rack fixed in said frame
at the bottom of the recess, one or more
brackets carried by said sash, a spindle fixed
5 in said bracket, a hollow gear rotatable on
said spindle meshing with said rack, a disc
keyed centrally of said spindle, discs ro-

tatable on said spindle engaging the sides
of said fixed discs, and opposed torsional
springs abutting the outer sides of said loose ¹⁰
discs and the inner sides of said gear.

In witness whereof I affix my signature.

STANLEY LADINSKY.
